UNITED STATES PATENT OFFICE.

ST. CLAIR LEWARK, OF MAMIE, NORTH CAROLINA.

SUBMARINE LIFE-BOAT.

1,259,534.

Specification of Letters Patent. Patented Mar. 19, 1918.

Application filed July 9, 1917. Serial No. 179,396.

To all whom it may concern:

Be it known that I, ST. CLAIR LEWARK, a citizen of the United States, and a resident of Mamie, in the county of Currituck 5 and State of North Carolina, have invented a new and useful Improvement in Submarine Life-Boats; of which the following is a specification.

My present invention relates generally to 10 submarine lifeboats and more particularly to a surface boat attached to a submarine or underwater boat in such manner as that it may be readily and quickly detached, and of such construction that when detached, 15 it will promptly rise to the surface of the water, the lifeboat having means to prevent the same from sinking and which tend to maintain the same in upright position in use, the objects of my present improvements 20 having to do with the construction of the lifeboat here presented and the connections between the same and a submarine or undersea boat whereby the lifeboat may, as above stated, be quickly detached for independent use.

These various objects and the advantages resulting from my invention will be apparent in the course of the following description in which reference is made to the 30 accompanying drawings, forming a part of this specification, and wherein—

Figure 1 is a vertical longitudinal section through my improved lifeboat illustrating the same in operative connection with a submarine,

Fig. 2 is an enlarged sectional view through certain of the connected portions of the lifeboat and submarine,

Fig. 3 is a sectional view similar to Fig. 40 1 with the lifeboat in detached relation to the submarine, as the former starts to rise to the surface,

Fig. 4 is a vertical cross section taken substantially on line 4—4 of Fig. 1,

Fig. 5 is an enlarged fragmentary section, being a portion of a submarine as seen in Fig. 3,

Fig. 6 is an enlarged sectional view of a portion of the lifeboat to be hereinafter 50 specifically referred to.

Figs. 7 and 8 are respectively a plan view and a longitudinal section of the lifeboat detached and upon the surface of the water.

Referring now to these figures generally, 55 my invention contemplates the provision

of a lifeboat 10 in connection with a submarine, a portion of the upper or deck plate 11 of which is seen in Figs. 1 to 5, inclusive. The lifeboat, of which there may be one or more to each submarine, may be 60 secured upon the latter at any desired point upon the deck thereof, the particular location being unimportant in so far as the present invention is concerned. To effect the normal connection of the lifeboat, however, it is provided with a centrally located projecting cylinder 12 disposed perpendicular to the longitudinal axis of the boat, and provided with an inwardly extending horizontal flange 13 adjacent its inner end, the 65 flange 13 terminating in an annular portion 14 spaced inwardly beyond and parallel with the cylinder 12 and surrounding an opening between the open inner and outer ends of the cylinder.

The cylinder 12 also has at its inner end a spaced surrounding annulus 15, the edge of which is flared at 16 and between which and the inner end of the cylinder is disposed a packing ring 17 to receive the outer open 80 end of a cylinder 18 extending from the deck 11 of the submarine and into which the cylinder 12 telescopes in spaced relation. The cylinder 18 of the submarine has a spaced inner annular rib 19 between which 85 and the inner end of the cylinder is disposed a packing ring 20 receiving thereagainst the free end of the cylinder 12 in the same manner in which the free end of the submarine cylinder 18 is received by the packing strip 90 17. In this way, taking into consideration the rigid connection of the lifeboat upon the submarine as presently described, the entrance of water within the telescoping cylinders 12 and 18 in connected position 95 as seen best in Fig. 2 is obviously prevented.

The submarine cylinder 18 has an inwardly projecting horizontal flange 21 at its inner end terminating in an inwardly projecting annular rib 22 similar to the rib 100 14 of the flange 13, before described, and against these ribs 14 and 22 are respectively disposed hatches or covers 23 and 24, each thereof being closed against the ribs 14 and 22 in a direction away from the submarine 105 and toward the lifeboat, so that their means of connection may in each instance be the same. The means of connection of the hatches or covers 23 and 24 being the same, the means connecting the hatch 23 of the 110

lifeboat will be understood as applying equally to the means connecting the hatch or cover 24 of the submarine.

The flange 13 has angularly offset lugs 25 in which are swiveled the headed ends of angular connecting bolts 26, the free extremities of which are shiftable to lap the peripheral edge of the hatch or cover 23 and are provided with bearings through which 10 are threaded clamping screws 27 bearing against the adjacent face of the hatch or cover adjacent its peripheral edge to press the latter toward the rib 14, the opposite face of the hatch or cover having a peripheral flange 28 and a similar flange 29 spaced inwardly beyond the peripheral flange 28 for the reception of a packing ring 30 which receives the outer edge of the rib 14.

The inner annular flange 29 of the hatch 20 or cover has a horizontally projecting annular ledge 31 paralleling the body of the cover or hatch to provide for engagement by the flanged ends 32 of clamping screws 33 threaded through the extremities of angular clamping bolts 34, the opposite threaded ends of which are swiveled in angular brackets 35 of the flange 13 at the opposite sides of the latter from the lugs 25, before mentioned, and in which the said bolts 34 25 are shiftable into and out of operative position, the same as the angular bolts 26 before described.

In this manner each of the hatches or covers 23 and 24 may be securely held in 35 closed position against the respective ribs 14 and 22 from each side, that is, either from the inside or the outside of both the lifeboat and the submarine.

With the parts in the position shown in 40 Fig. 2 it is obvious that the occupants of the submarine by releasing the clamping screws 27 of the cover 24 may remove the latter and by releasing the clamping screw 27 of the cover 23 may find their way into 45 the lifeboat 10, the cover 24 of the submarine being first closed by means of the clamping screws 33 and the cover 23 of the lifeboat being similarly closed by the clamping screws 33 thereof before the securing means 50 of the lifeboat are released.

It is obvious from the foregoing that the telescoping cylinders 12 and 18 of the lifeboat and submarine respectively extend sufficiently beyond their respective parts for 55 coöperation in the manner previously described and that so far as the present invention is concerned they may be either secured to their respective parts, as shown, or may be formed in connection therewith and as an 60 integral part thereof in the first instance, one of the advantages of my invention being its adaptability to submarines already in use as well as those in course of construction.

65 In the case of the lifeboat 10 its cylinder

12 projects from a deck plate or plates 36 extending the full length thereof between end air bulkheads 37 and provided adjacent the air bulkheads with rigid internally threaded sockets 39 for outwardly projecting 70 screw shafts 40 having hand wheels 41 at their inner ends located in the hold space of the lifeboat between the deck 36 and the sides and bottom of the boat in which the occupants are housed after leaving the submarine in the manner previously described and between the time of the detachment of the lifeboat from the submarine and its arrival upon the surface of the water due to 75 its buoyancy.

The submarine is similarly provided with threaded sockets 42 for the reception of the outer ends of the screw shafts 40 of the lifeboat and with threaded bearings 43 for outwardly projecting screw shafts 44 having 80 hand wheels 45 at their inner ends within the submarine. The use of the screw shafts 44 of the submarine is not essential and is merely supplemental to the screw shafts 40 of the lifeboat, the latter of which must be used in view of the fact that the screw shafts 44 of the submarine would be required to be released before the occupants proceeded into the lifeboat, whereas it is necessary that the lifeboat remain connected to the submarine until the occupants are within the hold of the lifeboat and the hatches or covers 23 secured by the clamping screws 33 as previously described.

Referring now to Figs. 7 and 8 it will 100 be noted that in addition to its end air bulkheads 37, the lifeboat 10 has end compartments 46 and 47 for provisions and fresh water and that it has spaced rectangular casings 48 extended transversely across the external surface of its deck 11 forming additional air chambers in connection with longitudinal air casings 49 along the sides 50 projecting beyond the deck plate 11, the transversely disposed casings 48 and the longitudinal casings 49 forming seats for the occupants of the boat on the surface of the water in addition to their buoyant functions, which latter, considering their particular disposition, tend to maintain the boat in upright position in connection with a heavy keel 51.

The upwardly projecting portions 50 just above referred to are provided with apertures 52 adjacent the external surface of the 120 deck 11 so as to drain any water inclosed in the space between the side portions 50 either from waves or trapped in this space as the lifeboat turns in the water in ascending to the surface from the position shown in Fig. 125 3, after release from the submarine.

It is obvious that in so ascending and turning to its righted position, the lifeboat being inverted as before stated in its connection upon the submarine, considerable wa- 130

ter will be trapped within the cylinder 12 of the lifeboat externally of its hatch or cover 23, and in order that this water may be released before the hatch or cover is opened 5 upon the surface of the water, the flange 13 receives one end of a pipe 53 as best seen in Fig. 6, the opposite end of which is threaded through the cylinder 12 to communicate with the exterior thereof adjacent the packing 10 ring 17. Thus the major portion of pipe 53 projects within the hold space of the lifeboat which extends to the flange 13 and the cover 23, and the pipe 53 being provided with a valve 54 which is normally closed, the 15 latter may be opened previous to the removal of the hatch or cover 23 and the water from within the cylinder 12 may be allowed to drain out.

It is obvious from the foregoing that my 20 invention provides a lifeboat which may be used to great advantage in the saving of life and property in case the engine of a submarine become disabled beyond repair while submerged, as long as the submarine is not 25 filled with water or its crew unconscious, as well as one which will permit transfer of the crew from the submarine to the lifeboat without getting water into either the submarine or the lifeboat. It is furthermore ob- 30 visible that my invention may be utilized to great advantage in view of the ready and quick detachment thereof from the submarine and rise to the surface in perfect safety and from various depths as well as its adaptability to the carrying of hawsers and other 35 connections from the submarine to the surface so that the former may thereafter be readily located and raised where it is disabled without total destruction.

40 It is furthermore obvious that my invention provides a life boat of the present character which is practically unsinkable unless totally destroyed and which may be built in various sizes and utilized in various ways in 45 connection with submarines as well as with varieties of particular fittings beyond those described and common to various other types of surface boats.

I claim:—

50 1. The combination with a submarine, of a lifeboat inverted and detachably secured thereon, said lifeboat and submarine having telescoping tubular extensions projecting therefrom and providing for communica- 55 tion therebetween, each of said tubular extensions being provided with a packing ring at its inner end to receive the outer end of the opposite extension, and each being provided with an inwardly projecting flange 60 having an annular rib around its inner edge, a hatch or cover for each of the extensions provided with a packing ring to receive the rib of its respective flange, and securing means at the inner and outer sides of each 65 of said flanges for engagement with the

hatches or covers at the inner and outer sides of the latter.

2. The combination with a submarine, of a lifeboat inverted and detachably secured thereon, said lifeboat and submarine having 70 telescoping cylinders in water tight relation establishing communication between the lifeboat and the submarine, each of said cylinders being provided with an inwardly projecting annular flange having an annular 75 rib around its inner edge, and each flange having external and internal brackets, a hatch or cover arranged to close against the rib of each of said cylinder flanges, and means supported by the said brackets for 80 engagement with portions of the hatch or cover at both the inner and outer sides thereof.

3. The combination with a submarine, of a lifeboat inverted and detachably secured 85 thereon, said lifeboat and submarine having telescoping cylinders in water tight relation establishing communication between the lifeboat and the submarine, each of said cylinders being provided with an inwardly 90 projecting annular flange having an annular rib around its inner edge, and each flange having external and internal brackets, a hatch or cover arranged to close against the rib of each of said cylinder flanges and 95 means movably connected to the said brackets and shiftable with respect to the hatch or cover for clamping engagement with portions thereof at both the inner and outer sides thereof.

4. The combination with a submarine, of a lifeboat inverted and detachably secured thereon, said lifeboat and submarine having 100 telescoping cylinders in water tight relation establishing communication between 105 the lifeboat and the submarine, each of said cylinders being provided with an inwardly projecting annular flange having an annular rib around its inner edge, and each flange having external and internal brackets, a 110 hatch or cover arranged to close against the rib of each of said cylinder flanges, angular bolts swiveled in connection with the said brackets of the flanges at the inner and outer sides thereof, and clamping screws threaded 115 through the free ends of said bolts for engagement with portions of the hatches or covers at the inner and outer sides of the latter.

5. A lifeboat of the character described 120 having air tight bulkheads in the forward and rear parts thereof and having a deck extending between the said bulkheads forming a closed hold, and casings extending above the deck and forming air compart- 125 ments for the purpose described.

6. The combination with a submarine, of a lifeboat secured thereon in inverted position and detachable therefrom, said lifeboat and submarine having telescoping en- 130

- 4.
- gaged cylinders establishing communication therebetween, a cover or hatch for each of the said cylindrical extensions to close the same and means carried by the said cylindrical extension of the lifeboat and controlled from a point inwardly beyond the cover thereof to drain water from the space above the cover when the lifeboat is released from the submarine and is righted. 5
- 10 7. The combination with a submarine, of a lifeboat secured thereon in inverted position and detachable therefrom, said lifeboat and submarine having telescopingly engaged cylinders establishing communication there- 15 between, a cover or hatch for each of the said cylindrical extensions to close the same and means carried by the said cylindrical extension of the lifeboat and controlled from a point beyond the cover thereof to drain 20 water from the space above the cover when the lifeboat is released from the submarine and is righted, said means including a pipe, one end of which communicates with the
- space within the cylindrical extension above the cover and the other of which communicates through the wall of the cylinder, the pipe having a valve located in the cylinder inwardly beyond the cover. 25
8. A lifeboat of the character described having a closed deck forming a hold below the same, said boat being provided with end air compartments and with casings disposed upon the upper surface of the said deck and also forming air compartments. 30
9. A lifeboat of the character described having a closed deck forming a hold below the same, said boat being provided with end air compartments and with casings disposed upon the upper surface of the said deck, said last named casings extending trans- 35 versely across the deck and forming seats. 40
